UNITED STATES PATENT OFFICE.

HUGH M. ROSS, OF WOODHAVEN, NEW YORK, ASSIGNOR TO ADRIANCE MACHINE WORKS, INC., OF BROOKLYN, NEW YORK, A CORPORATION OF NEW YORK.

MACHINE FOR OPERATING ON SHEET MATERIAL

Application filed September 28, 1923. Serial No. 665,262

My invention relates to machines for operating on sheet material, this invention being an improvement on that disclosed and claimed in my United States Patent No. 5 1,445,718, dated February 20th, 1923. In machines such as that shown in the said patent an operation performing member, such as a dye or punch, is employed to operate on successive portions of the material in 10 rows or series.

The principal object of this invention is to provide improved means for producing a relative shifting or feeding movement between the sheet and the operation performing member.

Other objects, features and advantages of the invention will appear more fully in the following detailed description and appended claims.

20 The accompanying drawings forming a part of this specification illustrate a machine containing one embodiment of the invention.

In the drawings,
25 Fig. 1 is a side elevation of the machine,
some of the parts being shown in section;

Fig. 2 is a plan view illustrating means for supporting and holding the sheet while it is operated upon and parts of the operation performing mechanism and the mechanism for controlling the relative feeding movement between the sheet and the operation performing member or tool.

Fig. 3 is a cross section showing the sheet support.

Fig. 4 is a transverse sectional view taken substantially centrally of the die mechanism and showing in addition to such mechanism parts of the means for controlling the lateral movement of the sheet operated upon.

Fig. 5 is a view partly in section and partly in plan showing part of the mechanism for controlling the direction of the aforesaid relative feeding movement.

Fig. 6 is an elevation of the sheet carrier forming part of the machine as disclosed.

Referring to Fig. 1, the base *a* of the machine carries a frame *b* which is tilted at a suitable angle to the vertical. In this frame is journaled the main driving shaft *c* which may be driven by any suitable means, such as the pulley *d*. At the back of the bed of the frame *b* is arranged the lower member *j* (see Figs. 2 and 4) of the die or punch mechanism, the upper member *k* of which

(Fig. 4) is carried by a plunger guided in suitable ways in the frame *b* and actuated from a crank *m* on the shaft *c* by the pitman 10 (see Fig. 1).

The frame *b* is provided with a sheet support or table *o*. For limiting the rearward movement of the sheet and insuring the proper positioning thereof in a fore and aft direction relative to the die, straight edges *x* are employed, each of which is formed of a strip of angle iron against one flange of which the rear edge of the sheet is adapted to bear.

When the sheet is introduced into the machine with its rear edge in contact with the straight edges, it is received by the carrier which is made to grip it and hold it firmly and to feed it lengthwise of the table *o* under the reciprocating punch member. 70

Referring more particularly to Figs. 4 and 6 this carrier comprises a rack bar 4 having square teeth along its front edge. Near each end of the rack bar 4 is secured a supporting bracket 9 provided with a pivoted presser or sheet gripper 13. The gripper is adapted to be forced into gripping relation to the sheet by the operation of the shaft 17 operated by handle 18. For a more detailed description of the gripper and its operation attention is directed to the above mentioned United States Patent No. 1,445,718. The carrier is moved longitudinally with respect to the table *o* by mechanism driven from the main shaft *c*. To this end the shaft *c*, as shown, has secured thereto a

sprocket wheel 20 which drives a chain 21 which in turn drives a sprocket wheel 22 (see Figs. 1 and 5). The sprocket wheel 22 is secured to a beveled gear 23 which meshes with and drives beveled gears 24 and 25, 95 respectively, in opposite direction about the shaft 26 on which the gears 24 and 25 are loosely mounted. Either of the gears 24 and 25 may be secured in driving relation to the shaft 26 by a clutch member 27 mounted upon the shaft 26 and movable along said shaft into operative relation to either of the gears 24 or 25 by mechanism which will be more fully described hereinafter. The clutch 27 may be of any suitable type, for example, a double friction clutch, the opposite sides of which are constructed and operate as shown in U. S. patent to Johnson 1,079, 105 348. The shaft 26 (see Figs. 1 and 2) has secured thereto a gear 27' meshing with a 110

gear 28 loosely mounted on shaft 29 and adapted to drive sprocket wheel 30 through a suitable yielding or slip coupling.

The slip coupling shown, which is of the friction type, includes friction discs 31 and 32 engaging opposite faces of the sprocket 30, the disk 32 bearing against the upper face of the gear 28. In order to maintain the proper amount of friction between the discs 31 and 32 and the sprocket 30 and gear 28, a spring 33 is provided. This spring exerts a yielding axial thrust against a nut 34 secured on the shaft 29, tending to lift the said shaft and thereby holding the discs 31 and 32 and the sprocket 30 with the desired degree of pressure between the gear 28 and the friction member 35 carried by the support 36. The amount of friction may be regulated by adjustment of the nut 34 upon the shaft 29. To facilitate release of the coupling, a lever 37 is pivoted as at 38 and arranged to bear upon the upper surface of the nut 34; so that by elevation of the outer end of the lever 37 the shaft 29 may be depressed and the coupling released.

A chain 39 (see Figs. 1 and 2) meshes with the sprocket 30 and also with idle sprockets 40, 41, 42, 43 and 44, the ends of this chain being secured to the respective ends of the rack 4 of the sheet carrier, as shown in Fig. 6. The sprocket 44 is arranged to hold the chain 39 in operative relation to the sprocket 30 and to this end it is, as shown, arranged in proximity to the sprocket 30 in engagement with the opposite face of the chain 39.

The rotation of the sprocket 30 from the driving shaft *c* accordingly moves the chain 39 to shift the sheet carrier longitudinally of the machine to carry the material operated upon between the coacting punch members *j*, *l*. This tendency to move the sheet carrier is continuous throughout a complete stroke of the carrier during the rotation of the shaft *c*. But by reason of the slip coupling described above the feeding of the sheet carrier may be arrested or prevented to enable the punch members *j*, *l* to operate upon the sheet material.

Referring to Fig. 4 the means shown for intermittently checking or arresting the sheet carrier comprises pawl 45 slidably mounted in the frame so as to cooperate with the teeth of the rack 4. The pawl 45 is operatively connected with one arm of a bell crank lever 46 which has the other arm connected by a link 47 with a lever 48. The lever 48 is connected by a link 49 (see Fig. 1) with a lever 50, also pivoted into frame *b* and carrying a roller 51 bearing upon cam 52 secured to the shaft *c*. The free end of the lever 50 is preferably shaped as a handle 50' so as to facilitate manual operation of the retaining pawl 45. A spring

53 holds lever 48 in such position that the roller 51 on lever 50 normally presses against the cam 52. The pawl 45 normally retains the rack (and also the carrier) against advance; but on each rotation of the shaft *c* the forward end of lever 50 is momentarily depressed by the cam 52 and the pawl 45 is withdrawn from the rack, releasing the rack but quickly returning it to engagement with it. There is thus effected an intermittent advance of the sheet across the machine, the several increments of advance depending upon the distance between the teeth upon the rack.

Suitable means are desirably provided for cutting away the scrap at the back of the sheet after the operation of the punch members *j*, *l*. Mechanism for this purpose is fully illustrated in my aforesaid Patent No. 1,445,718 and is thought to need no detailed description herein. It is desirable to provide automatic means to release the sheet material from the carrier at the end of each stroke to permit the sheet to fall back to its new position against straight edge *x*. Suitable means for this purpose are also illustrated in said Letters Patent No. 1,445,718.

My invention also contemplates the provision of mechanism whereby the clutch member is automatically shifted to effect the reversal of the feeding movement of the sheet carrier whenever the carrier has completed substantially a full stroke in one direction. To this end the shaft 17 of the carrier is provided with end portions 60 each of which is adapted to engage and shift an arm 61 pivoted as at 62, (see Fig. 1) at the end stroke of the carrier. The arms 61 are arranged at opposite sides of the machine and are connected by a link 63 (see Fig. 2) so as to be shiftable simultaneously. Movement of the carrier at the end portion of one stroke accordingly effects the movement of both arms 61 in one direction while the movement of the carrier on the succeeding stroke moves the arms 61 in the opposite direction, etc. Arm 61 (referring to Fig. 2) is connected by a link 64 (Figs. 1 and 2) to one arm of a bell crank lever 65 (see Figs. 2 and 5). The other arm of the lever 65 is connected by a link 66 to the clutch member 27. The shifting of the arm 61 by the carrier accordingly effects shifting of the clutch 27 to secure first one of the gears 24 or 25 into driving relation to the shaft 26 and then the other, to thereby cause the shaft 26 to be driven alternately in opposite directions and thereby automatically change the direction of the feeding movement of the carrier at the end of each stroke thereof.

In operation, a sheet having been placed upon the table *o* so that the gripping means of the carrier will fall with its rear edge into contact with the straight edges *x*, the op-

erator starts the machine. The sheet being firmly locked in the carrier, the latter under the continuous influence of the driving means, including the slip coupling, 5 moves across the machine except when prevented by the pawl 45, at which time the slip coupling yields and permits stoppage of the carrier. Each time after the punch mechanism has operated, the carrier moves 10 on one step so as to bring the sheet into position for performing the next punching operation. At the end of the stroke of the carrier, the scrap having been cleared away and the sheet having fallen back with its 15 rear edge into contact with the straight edges, the carrier travels in the opposite direction. The operation of the mechanism on the rear movement of the carrier is the same as it was upon the advance thereof. 20 The automatic operation of the machine may be continued throughout successive rows of operation by the punch members *j*, *k* until the entire sheet has been operated upon. 25 It will be seen that my invention results in a machine which is simple in construction, which requires no expert attention to keep it in operative condition and which is quick and economical in operation. It is 30 to be understood that this invention is not to be limited to the details shown and described and that many modifications and changes may be made without departing from the spirit of my invention and the 35 scope of the appended claims.

Having thus described my invention, what I claim as new and desire to secure by Letters Patent is:—

1. The combination of a framework, operation performing means supported thereby, means for holding the material to be operated upon, means tending to produce a continuous feeding movement of said holding means with respect to said operation performing means, said movement producing means including a yielding coupling, and means controlled by said operation performing means for intermittently preventing such relative movement against the action of said movement producing means.

2. The combination of operation performing means, means for holding the material to be operated upon, movement producing means tending to produce a continuous relative feeding movement in either of two opposite directions between said operation performing means and said holding means to effect operative positioning of successive portions of the material in each of said 60 directions, said movement producing means including a slip coupling, means mounted at each end of a path of movement of said holding means for controlling said movement producing means to reverse the same at the 65 end of such movement in one direction, and

means for intermittently preventing such relative movement when said movement producing means is operating in either direction.

3. The combination of operation performing means, means for holding the material to be operated upon, movement producing means tending to produce a continuous relative feeding movement in either of two opposite directions between said operation performing means and said holding means to permit operative positioning of successive portions of the material in each of said directions, said movement producing means including a friction coupling and a flexible 70 elongated member between said coupling and said holding means, means provided with an operating element at each end of the path of movement of said holding means for controlling said movement producing means to reverse the same automatically at the end of such movement in one direction, and automatic means for intermittently preventing such relative movement when said movement producing means is operating in 75 either direction.

4. The combination of a movable carrying device for material to be operated upon, means tending to produce a continuous feeding movement of said device, said movement producing means including a rotary slip coupling and a flexible elongated member between said coupling and said carrying device, and means for intermittently preventing such movement against the action 80 of said movement producing means.

5. The combination of a tool, a carrier for the material to be operated upon by the tool and means for producing a relative feeding movement in opposite directions between said tool and said carrier including a driving member and a slip coupling driven therefrom, whereby said feeding movement may be arrested without stopping said driving member, and means operated by 85 said carrier for controlling the direction of the said feeding movement.

6. The combination of a tool, means for operating the same, a carrier for the material to be operated upon by the tool and means for producing a relative feeding movement in opposite directions between said tool and said carrier including a driving member and a slip coupling driven therefrom, mechanical means controlled by said operating means whereby said feeding movement may be arrested without stopping said driving member, and means governed by the position of said carrier for controlling the direction of the said feeding movement to 115 automatically reverse the same after a predetermined extent of said movement.

7. The combination of a tool, a carrier for the material to be operated upon by the tool and means for producing a relative 120

feeding movement in opposite directions between said tool and said carrier including a driving member and a slip coupling driven therefrom, means including a rack and a movable pawl coacting therewith whereby said feeding movement may be arrested without stopping said driving member, and means including a clutch having an operating member at each end of the path of movement of said carrier to control the direction of the said feeding movement to automatically reverse the same after a predetermined extent of said movement.

8. The combination of a frame, an inclined carrier movably supported thereby and provided with means for releasably securing a sheet to the same, means for moving the carrier in opposite directions including a slip coupling, automatic means for intermittently checking the carrier, and automatic means for releasing said securing means to permit movement of the sheet by gravity transversely to the movement of the carrier after the carrier has moved a predetermined extent.

9. The combination of a framework, operation performing means supported thereby, means for holding the material to be operated upon, means tending to produce a continuous feeding movement of said holding means with respect to said operation performing means, said movement producing means including a yielding coupling, and means controlled by said operation performing means and including a rack and a movable pawl arranged to coact with said rack for intermittently preventing such feeding movement against the action of said movement producing means.

10. The combination of operation performing means, means for holding the material to be operated upon, movement producing means tending to produce a continuous relative feeding movement in either of two opposite directions between said operation performing means and said holding means to effect operative positioning of successive portions of the material in each of said directions, said movement producing means including a slip coupling and a flexible elongated member between said coupling and said holding means, means mounted at each end of a path of movement of said holding means for controlling said

movement producing means to reverse the same at the end of such movement in one direction, and means for intermittently preventing such relative movement when said movement producing means is operating in either direction.

11. The combination of operation performing means, means for holding the material to be operated upon, movement producing means tending to produce a continuous relative feeding movement in either of two opposite directions between said operation performing means and said holding means to effect operative positioning of successive portions of the material in each of said directions, said movement producing means including a slip coupling, means mounted at each end of a path of movement of said holding means for controlling said movement producing means to reverse the same at the end of such movement in one direction, and means including a rack and a movable pawl coacting therewith and controlled by said operation performing means for intermittently preventing such relative movement when said movement producing means is operated in either direction.

12. The combination of operation performing means, means for holding the material to be operated upon, movement producing means tending to produce a continuous relative feeding movement in either of two opposite directions between said operation performing means and said holding means to effect operative positioning of successive portions of the material in each of said directions, said movement producing means including a slip coupling and a flexible elongated member between said coupling and said holding means, means mounted at each end of a path of movement of said holding means for controlling said movement producing means to reverse the same at the end of such movement in one direction, and means including a rack and a movable pawl coacting therewith and controlled by said operation performing means for intermittently preventing such relative movement when said movement producing means is operating in either direction.

In testimony whereof, I have signed my name to this specification.

HUGH M. ROSS.
